CLAIM

The ornamental design for an access-resistant jar, as shown and described.

DESCRIPTION

FIG. 1 is a top perspective view of an access-resistant jar of the present invention, shown in the closed condition; FIG. 2 is a bottom perspective view thereof; FIG. 3 is a front side elevation view thereof; FIG. 4 is a right side elevation view thereof; FIG. 5 is a rear elevation view thereof; FIG. 6 is a left side elevation view thereof; FIG. 7 is a top plan view thereof; FIG. 8 is a bottom plan view thereof; FIG. 9 is a top perspective view of the closure portion of the access-resistant jar of FIGS. 1-8 with the jar portion removed; FIG. 10 is a bottom perspective view thereof; FIG. 11 is a front side elevation view thereof; FIG. 12 is a right side elevation view thereof; FIG. 13 is a rear elevation view thereof; FIG. 14 is a left side elevation view thereof; FIG. 15 is a top plan view thereof; FIG. 16 is a bottom plan view thereof; FIG. 17 is a top perspective view of the jar portion of the access-resistant jar of FIGS. 1-8 shown in the open condition with the closure removed; FIG. 18 is a bottom perspective view thereof; FIG. 19 is a front side elevation view thereof; FIG. 20 is a right side elevation view thereof; FIG. 21 is a rear elevation view thereof; FIG. 22 is a left side elevation view thereof; FIG. 23 is a top plan view thereof; FIG. 24 is a bottom plan view thereof; FIG. 25 is an exploded top perspective view of the access-resistant jar of FIGS. 1-24; FIG. 26 is a top perspective view of a second embodiment of the present invention, shown in the closed condition; FIG. 27 is a bottom perspective view thereof; FIG. 28 is a front side elevation view thereof; FIG. 29 is a right side elevation view thereof; FIG. 30 is a rear elevation view thereof; FIG. 31 is a left side elevation view thereof; FIG. 32 is a top plan view thereof; FIG. 33 is a bottom plan view thereof; FIG. 34 is a top perspective view of the closure portion of the access-resistant jar of FIGS. 26-33 with the jar portion removed; FIG. 35 is a bottom perspective view thereof; FIG. 36 is a front side elevation view thereof; FIG. 37 is a right side elevation view thereof; FIG. 38 is a rear elevation view thereof; FIG. 39 is a left side elevation view thereof; FIG. 40 is a top plan view thereof; FIG. 41 is a bottom plan view thereof; FIG. 42 is a top perspective view of the jar portion of the access-resistant jar of FIGS. 26-33 shown in the open condition with the closure removed; FIG. 43 is a bottom perspective view thereof; FIG. 44 is a front side elevation view thereof; FIG. 45 is a right side elevation view thereof; FIG. 46 is a rear elevation view thereof; FIG. 47 is a left side elevation view thereof; FIG. 48 is a top plan view thereof;

FIG. 49 is a bottom plan view thereof; and,
FIG. 50 is an exploded top perspective view of the access-
resistant jar of FIGS. 26-49.

The broken lines in the drawings illustrate the portions of the
access-resistant jar that form no part of the claimed design.
